CLAIM

The ornamental design for a body of cutting tool for processing a valve sheet, as shown and described.

DESCRIPTION

FIG. 1 is a front view of a body of cutting tool for processing a valve sheet showing my new design;

FIG. 2 is a rear view thereof;

FIG. 3 is a top view thereof;

FIG. 4 is a bottom view thereof;

FIG. 5 is a right side view thereof;

FIG. 6 is a left side view thereof;

FIG. 7 is a perspective view thereof;

FIG. 8 is a cross sectional view taken along line VIII-VIII of FIG. 1;

FIG. 9 is a cross sectional view taken along line IX-IX of FIG. 5;

FIG. 10 is a cross sectional view taken along line X-X of FIG. 5;

FIG. 11 is a cross sectional view taken along line XI-XI of FIG. 5;

FIG. 12 is a cross sectional view taken along line XII-XII of FIG. 5;

FIG. 13 is an enlarged cross sectional view of XIII-XIII portion of FIG. 8; and,

FIG. 14 is an enlarged cross sectional view of XIV-XIV portion of FIG. 11.

The broken lines shown in the drawings represent portions of the body of cutting tool for processing a valve sheet that form no part of the claimed design.

The long dashed and short dashed line indicates only a boundary between the portion sought to receive design registration as a partial design and the other portions.
